(57) **CLAIM**

We claim the ornamental design for a temperature gauge for oven range, as shown and described.

DESCRIPTION

FIG. 1 is a perspective view of a temperature gauge for oven range showing our new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view thereof, showing a state of its holder opened;

FIG. 9 is a perspective view thereof, showing an illustration of use; and,

FIG. 10 is a perspective view thereof, showing a place where the temperature gauge for oven range is located in an oven range.

The broken lines depict environmental structure that forms no part of the claimed design. The dot-dash lines in FIG. 10 indicate a position where the temperature gauge for oven range is located.
